(57) **CLAIM**

The ornamental design for a ring candy confection, as shown and described.

DESCRIPTION

FIG. 1 is a top, front and left side perspective view of a ring candy confection showing my new design;

FIG. 2 is a bottom, front and right side perspective view thereof;

FIG. 3 is a top plan view thereof;

FIG. 4 is a bottom plan view thereof;

FIG. 5 is a right side elevation view thereof, the left side elevation view being a mirror image thereof;

FIG. 6 is a front elevation view thereof; and,

FIG. 7 is a rear elevation view thereof.

The broken lines shown are included for the purpose of illustrating the unclaimed portions of the article and form no part of the claimed design.
